Primary Examiner — Ricky Pham(57) **CLAIM**

The ornamental design for a shave ice attachment, as shown and described.

DESCRIPTION

FIG. 1 is a front, bottom perspective view of a shave ice attachment, showing my new design;

FIG. 2 is a rear, top perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the area labeled 9 in FIG. 1 thereof;

FIG. 10 is an enlarged view of the area labeled 10 in FIG. 1 thereof; and,

FIG. 11 is an enlarged view of the area labeled 11 in FIG. 2. The dashed lines in the figures illustrate portions of the shave ice attachment that form no part of the claimed design. The dot-dash-dot broken lines of the shave ice attachment in FIG. 1 illustrate a boundary and cut line of the enlarged view in FIG. 9 and FIG. 10 and form no part of the claimed design.

The dot-dash-dot broken lines of the shave ice attachment in FIG. 2 illustrate a boundary and cut line of the enlarged view in FIG. 11 and form no part of the claimed design.
